UNITED STATES PATENT OFFICE.

HARRY T. KINGSBURY AND EDWARD J. KINGSBURY, OF KEENE, NEW HAMPSHIRE.

DESIGN FOR A PORTABLE BABY-SWING.

55,384.

Specification for Design.

Patented June 1, 1920.

Application filed September 15, 1919. Serial No. 324,027. Term of patent 7 years.

To all whom it may concern:

Be it known that we, HARRY T. KINGSBURY and EDWARD J. KINGSBURY, citizens of the United States, residing at Keene, in the county of Cheshire and State of New Hampshire, have invented a new, original, and ornamental Design for a Portable Baby-Swing, of which the following is a specification, reference being had to the accompanying drawing, forming part thereof.

The figure is a perspective view of a portable baby swing, showing our new design.

We claim:

The ornamental design for a portable baby swing, as shown.

In testimony whereof, we affix our signatures.

HARRY T. KINGSBURY.
EDWARD J. KINGSBURY.
